UNITED STATES PATENT OFFICE.

THOMAS J. BUSH, OF LEXINGTON, KENTUCKY.

DIE FOR MAKING BOLTS.

SPECIFICATION forming part of Letters Patent No. 446,281, dated February 10, 1891.

Application filed May 2, 1890. Serial No. 350,343. (No model.)

To all whom it may concern:

Be it known that I, THOMAS J. BUSH, of Lexington, in the county of Fayette and State of Kentucky, have invented a new and Improved Machine for Making Bolts, of which the following is a full, clear, and exact description.

My invention relates to making interlocking bolts such or substantially such as are shown in my patent of September 19, 1882, No. 264,622; and the invention consists of a machine comprising a die and a punch or mandrel constructed to face off and recess the end of the bolt to form a locking-shoulder, all as hereinafter described and claimed.

Reference is to be had to the accompanying drawings, forming a part of this specification, in which similar letters of reference indicate corresponding parts in all the views.

Figure 1 is a sectional elevation of the anvil and punch or mandrel, showing the formation of a bolt. Figs. 2 and 3 are transverse sectional views on the lines *x x* and *y y*, respectively, of Fig. 1. Fig. 4 is a perspective view of the punch or mandrel, and Fig. 5 is an enlarged perspective view of the lower end of the bolt.

A represents a die formed with a seat *A'* to receive the rod of metal from which the bolt *B* is to be formed. The said seat *A'* is cov-

ered, as at *A*², and a die is recessed at *A*³ to form a guide for the punch or mandrel *C*; but the cover *A*² may be omitted, if desired. The punch or mandrel is formed at its lower edge with a slant or bevel *c* to face off one side of the bolt, as at *b*. This slant is terminated abruptly by the recess *c'*, which forms the shoulder *c*², that makes the offset *b'* in the bolt. At the side of the recess *c'* is formed the projection *c*³, which forms the recess *b*² in the bolt.

In operation a plain bar of metal is placed in the seat of a die and the punch or mandrel is lowered upon it and heavy pressure is applied to it, so that the bolt is not only shaped but subjected to heavy compression, so that its strength is not materially decreased by the reduction in size incident to its formation.

Having thus described my invention, what I claim as new, and desire to secure by Letters Patent, is—

The mandrel *C*, formed with a sloping surface *c*, recess *c'*, and projection *c*³, to be used in connection with a die formed with a seat for the blank and an aperture for the mandrel, substantially as described.

THOMAS J. BUSH.
